UNITED STATES PATENT OFFICE

145,813

DESIGN FOR A GARMENT HOOK

Harold A. Marsh, Chestnut Hill, Mass.

Application March 11, 1946, Serial No. 127,342

Term of patent 3½ years

(Cl. D17—9)

To all whom it may concern:

Be it known that I, Harold A. Marsh, a citizen of the United States, residing at Chestnut Hill, in the county of Middlesex, State of Massachusetts, have invented a new, original, and ornamental Design for a Garment Hook or the like, of which the following is a specification, reference being had to the accompanying drawing, forming part thereof.

Fig. 1 is a front elevational view of a garment hook or the like showing my new design.

Fig. 2 is a side elevational view of a garment hook or the like.

Fig. 3 is a rear elevational view of a garment hook or the like.

Fig. 4 is a side elevational view of a garment hook or the like, with the garment supporting portion thereof extended.

Fig. 5 is a top plan view of a garment hook or the like, and

Fig. 6 is a bottom plan view thereof.

I claim:

The ornamental design for a garment hook or the like, as shown.

HAROLD A. MARSH.
